UNITED STATES PATENT OFFICE.

CHARLES L. RAYFIELD, OF CHICAGO, ILLINOIS, ASSIGNOR, BY MESNE ASSIGNMENTS, TO GENESEE CARBURETER COMPANY, OF FLINT, MICHIGAN, A CORPORATION OF INDIANA.

TWO-LEVEL MULTIJET CARBURETOR.

Application filed April 30, 1920. Serial No. 377,922.

This invention relates to that type of retor embodying the principles of my invention. 55 Figure 2 is an enlarged central vertical section taken through the carburetor with parts omitted and parts shown in elevation. Figure 3 is a central vertical section with 60 parts omitted and parts shown in elevation taken on the line 3—3 of Fig. 2. Figure 4 is a sectional detail on line 4—4 of Figure 2 with parts omitted and parts shown in elevation. 65 Figure 5 is a fragmentary detail section taken on line 5—5 of Figure 4. Figure 6 is an enlarged fragmentary detail section on line 6—6 of Figure 4 with parts in elevation. 70 Figure 7 is an enlarged detail section taken through the fuel nozzle of the carburetor. 75

The carburetor also comprehends a novel arrangement of passages from one of the chambers for supplying fuel beyond the throttle valve for priming the engine during starting as well as an ingenious arrangement and design of parts contributing toward the proper functioning of the device as an efficient and complete mechanism for supplying an explosive mixture of the proper proportions to an internal combustion engine for the various conditions of operation thereof. 80

It is an object therefore of this invention to provide a carburetor having a plurality of fuel supply chambers for supplying fuel to a number of fuel jets in a compound nozzle whereby the assembly of fuel jets affords a compensating supply means for the fuel to properly proportion the quantity of fuel admitted to the carburetor for various operating conditions of the engine. 85

40 It is a further object of this invention to provide a carburetor free from complicated moving parts and operating automatically to properly carbure the air entering the carburetor for admission to the engine. 90

45 Other and further important objects of this invention will be apparent from the disclosures in the drawings and specification. 95

My invention (in a preferred form) is illustrated in the drawings and hereinafter 50 more fully described.

Drawings.

Figure 1 is a side elevation of a carburetor.

The carburetor consists of a main casing 1 cast as an integral piece of metal having therein a chamber 2 with an outlet 3 in which is disposed a Venturi tube 4 secured by set screw 5 and lock nut 6. Also disposed in said outlet is a throttle valve 7 on an operating shaft 8 having a lever 9, and beyond said throttle valve the end of the casing is flanged as denoted by reference numeral 10 for attachment of the carburetor to the engine manifold. 85

Also formed within the casing 1 is an air inlet passage 11 provided with a butterfly valve 12 which is operated as a choker, and is mounted on a shaft 13 having an operating handle 14 exterior of the casing. Formed at one side of the chamber 2 is an overflow or standpipe chamber 15 vented at 15^a and having a drain aperture closed by a plug 16 in the lower end thereof, and at its upper end formed with an inlet passage 17 communicating into a fitting 18 in which is a screen 19, mounted on the end of a fitting plug 20. 95

Attached to the casing 1 on the under side thereof is a float chamber casing 21 having an extension 22 which is extended to one side and beneath the overflow chamber 15 and said float chamber casing 21 is provided with a drain outlet normally closed by a closure 100 plug 23. Threaded into the floor 24 of the

overflow casing 15 as shown in detail in Figure 6 is an upright tube or standpipe 25, and slidably therethrough is a triangular stem 26 of a needle valve closure 27 which at its upper end registers with an inlet passage of a plug member 28 threaded into the top wall of the overflow casing and communicating with the inlet passage 17. Mounted on the upper end of the stem 26 below the needle valve closure 27 is a hood or cap 29 having apertures 30 therethrough, said hood fitting over, though spaced above and away from the upper end of the standpipe tube 25. The lower end of the stem 26 of said needle valve rests upon a pivoted bar 31 attached upon a pivot extension 32 beneath the floor 24 within the side compartment 22 of the float chamber, and the end of said pivoted bar 31 is of yoke shape, and rests upon the upper surface of a float 33 slidably mounted within the float chamber to assume different levels therein according to the level of the fuel in said float chamber.

As shown in Figures 2 and 7 the floor of the chamber 2 is formed to afford substantially a hub 34 and threaded into the end thereof is a tube 35 provided with a sealing gasket 36. Threaded into the lower end of said hub 34 is a plug 37 with a sealing gasket 38 and engaged into said plug 37 is a downwardly extending tube 39 which projects through an aperture in the floor of the float chamber 2 and has threaded thereon in sealing relation, a nut 40. The float 33 of the float chamber is slidably mounted upon said tube or stem 39. Said tube 39 is provided with a port 41 near its upper end and another port 42 near its lower end both within the float chamber 21, but with the lower port 42 normally submerged in the fuel within the float chamber and the upper port 41 normally in the air space above the level of the fuel.

Threaded into the upper end of the upright tube 35 of the main fuel nozzle is an inner tube 43, having apertures 43^a 43^b and said tube 43 is spaced from the outer tube 35 to afford an annular chamber and extends downwardly to the same point as the tube member 35, and the outer tube 35 is provided with slits or outlet passages 44 at its upper end. Within the inner tube 43 is another tube 45 spaced therefrom to afford another annular chamber and said tube 45 at its lower end is threaded into the aperture of the member 37 and at its upper end is provided with apertures 46. Inserted within the tube 45 and spaced inwardly therefrom is the central tube of the fuel nozzle which is denoted by the reference numeral 47. The lower end of said central tube is secured into the lower end of the tube 39 and has a plug closure 48 therein.

Said tube 47 near its lower end is provided with apertures 49 and at its upper end,

at the tip of the nozzle, has a spacing washer or collar 50 therearound which engages with the upper end of the tube 45 to hold the tubes spaced from one another and thus afford an annular chamber therebetween. 70

It will be seen that the manner of assembly of the various tubes described, in the hub member 34, provides an annular chamber 51 within said hub member communicating with both of the annular chambers between the tubes 43 and 45, and the tubes 43 and 35. 75

As shown in detail in Figure 5 a passage 52 is formed in the casing 1 inclining slightly downwardly to the chamber 51 and 80 the passage 52 communicates with a vertical vent passage 53 formed in the wall of the overflow chamber 15 and as shown, is closed by a calibrated plug 54. Threaded into the floor of the overflow chamber 15 85 shown in Figure 5 and communicating with the passage 52 is an apertured plug 55 forming a seat for a needle valve closure 56, the stem 57 of which extends upwardly and is threaded into a plug 58 threaded through 90 an aperture in the top wall of the chamber 15. A detachable cap 59 is provided over the upper apertured end of the plug 58 which by removal, gives access to the stem 57 for adjustment of the needle valve. A cylindrical screen 60 is engaged in position concentrically about the needle valve 57, as its upper end engaged around the lower end of the plug 58 and its lower end around the upper end of plug 55. 100

As shown in Figure 3 a passage 61 is bored in the side of the float chamber 21 which registers with a passage 62 in the casing 1 and said passage 62 communicates into a lateral passage 63 which communicates through the inner wall of the casing 1 said passage 63 registering with a peripheral groove 64 on the venturi 4. An air inlet port 65 is provided through the casing 1 opposite to said passage 63 and also registering with said peripheral groove 64. The communication between the passage 63 and the peripheral groove or passage 64 is controlled by a manually adjustable needle valve 66 having a knurled head 67 and a spring impelled detent 68 to retain the same in adjusted position. Formed in the casing 1 at the side of the outlet extension 3 and communicating with passage 63, is a passage 69 which at its upper end is closed by a plug 70, but which passage 69 communicates into a laterally directed passage 71 leading into the outlet end of the carburetor beyond the throttle valve. The shaft 8, is provided with a passage 72 therethrough which registers with the passage 69 when the throttle valve 7 is closed, thus permitting a flow through the passage 69 to the passage 71. 115

As shown clearly in Figures 2 and 4 an air vent 73 for the float chamber 21 is pro- 120

vided in the floor of the chamber 2, and in the lower end of the float chamber 21 surrounding the tube 39 above the aperture 42 is a conical screen 74.

5

Operation.

The fuel is admitted into the carburetor by a pipe connection (not shown) through the fitting 20 flowing through the screen 19 and 10 passage 17 past the open needle valve 27 and spilling over the hood 29 into the overflow chamber 15. The level of the fuel continues to rise in the overflow chamber 15 finally reaching a height such that it flows over 15 and into the upper end of the standpipe 25 and downwardly therethrough into the float chamber 21, and as the float chamber fills the float 33 is elevated until a predetermined level is reached such that said float operates 20 the lever 31 to elevate the stem 26 of the needle valve 27, closing off the inlet of fuel to the overflow chamber. The apertures 30 in the hood 29 surrounding the upper end of the standpipe 25 serve to break any suction 25 effect between the overflow chamber and float chamber which might serve to siphon the fuel from the former into the latter.

The overflow chamber 15 is adapted to 30 supply fuel for one jet of the compound nozzle of the carburetor, and the float chamber 21 is adapted to supply fuel for another jet thereof in a manner hereinafter described. As shown in detail in Figure 5 35 there is an outlet for fuel from the standpipe chamber 15 past a needle valve 56 controlling the outlet of fuel into the passage 52 which leads to the chamber 51 surrounding the central portion of the compound fuel nozzle of the carburetor. The flow past the needle valve 56 into the passage 52 is entirely by gravity and ordinarily is not affected by a depression induced in the carbureting chamber at the nozzle of the carburetor. However, the upright vent passage 53 communicating with said outlet passage may be used to effect and control depression in the passage 52 by closing said vent passage with a plug 54 so that no air is admitted, or by reducing the suction effect in the passage 52 a certain amount, by use of any one of a number of plugs having different sized apertures therethrough. Then any desired depression in the passage 52 45 may be obtained which of course affects the quantity of fuel permitted to flow to the nozzle in accordance with the requirements and characteristics of the motor to which the carburetor is connected.

50 The fuel admitted into the chamber 51 from the standpipe chamber 15 past its controlling and adjustable needle valve rises in the annular passage between the outer tube 35 and the inner tubes 43 and 45. The fuel rises to a level corresponding to the level

of that in the standpipe chamber 15. Ordinarily the level of the fuel in the standpipe chamber corresponds to the level of the upper end of the fixed standpipe 25 and as shown in the dotted lines of Figure 2 the level of fuel in the annular chambers mentioned corresponds therewith and reaches upwardly to a point only slightly below the outlet slits 44.

The other fuel level which exists in the compound nozzle is that of the fuel in the float chamber 21, and by reference to Figure 7, it will be seen that the level of fuel rises in the central tube and in the annular passage surrounding the same, upwardly to a point below the aperture 41 of the tube 39.

The purpose of the needle valve 66 disposed in the priming passages 61, 62 and 69 of the carburetor is to regulate the amount of air allowed to leak into said priming passages from the air inlet 65 through the peripheral groove 64 of the venturi thereby regulating the suction and consequently the quantity of fuel which may be drawn upwardly through the priming passages and discharge into the carburetor outlet through the passage 71 beyond the throttle valve 7.

Assume that the motor is at rest and it is desired to start the same. The choker valve 12 is first closed and then the throttle valve 95 7. When the engine is turned over, the draft created will cause a flow of fuel to take place upwardly from the float chamber 21 through the priming passages 61, 62, 63 and 69 being discharged through the outlet 71 100 beyond the throttle valve 7, and of course the leakage of air past the throttle valve 7, together with the small quantity admitted past the needle valve 66, will serve to form a richly carbureted mixture which will insure easy starting of the motor. After the motor is started, the throttle valve 7 is opened an amount, within the discretion of the operator, and the choker valve 12 may also be opened an amount desired depending 105 upon the operating condition of the engine. In any event, the suction draft due to operation of the engine is imposed upon the tip of the compound fuel nozzle in the carbureting chamber at the neck of the venturi 4. 110 If this suction draft is not considerable, fuel will only be drawn from the nozzle through the slits 44 in the manner pointed out in the following.

The fuel level in the annular passages of 120 the fuel nozzle on each side of the tube 43 corresponds to that in the overflow chamber 15. The pressure on the level of fuel however in the outer annular chamber surrounding the tube 43 is that induced owing to the 125 suction draft on the nozzle, and the other level of fuel in the annular chamber inwardly of the tube 43, is under atmospheric pressure as will be seen in the following. The float chamber 21 is normally under 130

atmospheric pressure, owing to the provision of the air vent 73 in the top wall thereof and as a consequence owing to the provision of the port 41 in the lower tube 39, the 5 annular passage within said tube 39 surrounding the central tube 47 is under atmospheric pressure. This pressure effect is transmitted upwardly around the central tube 47 and is communicated thru the apertures 46 to the level of the fuel in the annular chamber surrounding the tube 45.

As a consequence the two levels in the respective annular chambers on each side of the tube 43 being subjected to different pressures, one atmospheric and the other a depression due to the suction draft through the carburetor, a change in levels of the fuel in the two chambers will take place causing the fuel to rise in the outer annular chamber 20 and flow outwardly through the slits 44, and, of course, fuel is continually supplied for this purpose from the standpipe chamber to the chamber 51. The rate of flow of fuel to the chamber 51 is of course slightly dependent upon the amount of closure of the passage 53 and the demand on the chamber 15.

Fuel is also supplied through the priming passage 71 for idling speeds of the engine 30 inasmuch as the communication with the float chamber through the throttle valve shaft aperture is not entirely cut off by the preliminary opening adjustments of the throttle valve. At all times any withdrawal 35 of fuel from the float chamber causing a lowering of the level of fuel therein, will cause the float controlled inlet valve 27 to the overflow chamber to open, thereby supplying fuel to the overflow chamber and by overflow therefrom, supplying fuel also to the float chamber.

In order to restrict the discharge of fuel 45 through the slits 44, in event of too great difference in pressure on the two levels within the two respective annular chambers a number of apertures 43^a and 43^b are provided in the tube 43 at different levels therein so that the suction or depression effect in the outer annular chamber is partially 50 broken as said apertures are uncovered due to the change in level of the fuel in the adjacent annular chamber. Fuel stands near the top of the nozzle at different levels in the annular chambers on both sides of the tube 43 during the operation of the engine. The fuel in the annular chamber within the 55 tube 43 is under atmospheric pressure owing to the passage through hole 41, the passage immediately surrounding the tube 47, and aperture 46. This passage communicates the atmospheric pressure of the lower fuel chamber to the top of the fuel in the annular passage within the tube 43. The fuel in the annular passage outside the tube 43 is subjected to the sub-atmospheric pressure

created in the Venturi tube as soon as the engine is started. The differences in pressure on the fuel in the inner and outer annular chambers causes the fuel to flow from the outer annular chamber into the intake passage. As the depression in the intake passage becomes greater, the flow is more rapid and the level of fuel in the inner annular chamber is lowered until one or more of the apertures 43^a, 43^b are uncovered. When 75 these apertures are uncovered air is permitted to flow therethrough. This action lessens the depression in the inner fuel chamber as the depression in the intake passage increases and air is mixed with the 80 fuel discharged from the nozzle. Thus a compensating effect is gained which serves to diminish the quantity of liquid fuel drawn from the nozzle through the slits 44 in proportion to the suction effect so that a 85 property carbureted mixture is obtained.

As the engine continues to operate, and the throttle valve is opened wider, of course, the suction effect is also imposed upon the central tube 47 sufficiently to cause fuel to be 90 drawn upwardly therethrough directly from the float chamber 21. However, the moment the level of the fuel in the float chamber 21 tends to change owing to withdrawal of fuel therefrom through the central nozzle 47, 95 movement of the float 33 will take place thereby lowering the lever 31. As a consequence as pointed out, lowering of the stem 26 carrying the needle inlet valve 27, takes place so that a flow of fuel is permitted into 100 the overflow chamber 15 continuing until said chamber 15 is entirely filled and the surplus fuel admitted thereto spills over the standpipe 25 and enters the float chamber 21 to restore the same to the predetermined 105 level. This of course will cause elevation of the float 33 and closure of the needle inlet valve 27 supplying the fuel into the standpipe chamber 15.

It is evident that the fuel can always be 110 supplied through the slits 44 of the compound nozzle from the overflow chamber 15, owing to the fact that fuel will at the same time be withdrawn from the float chamber 21, causing an additional supply of fuel to 115 be admitted into the overflow chamber.

I am aware that numerous details of construction may be varied through a wide range without departing from the principles of this invention and I therefore do not purpose limiting the patent granted further than necessitated by the prior art.

I claim—

1. In a carburetor of the class described, upper and lower fuel supply chambers, a 125 single nozzle therefor, an outer annular discharge passage in said nozzle for said upper chamber, a central discharge passage in said nozzle for said lower chamber, annular passages in said nozzle between said discharge 130

passages, one communicating with the top of said lower chamber, and the other communicating with the top of said upper chamber, said annular passages communicating with each other at their tops, and a vent for 20
5 with each other at their tops, and a vent for said lower chamber, said lower chamber venting said upper chamber through said communicating passages.

2. In a carburetor of the class described,
10 upper and lower fuel supply chambers, a single nozzle therefor, an outer annular discharge passage in said nozzle for said upper chamber, a central discharge passage in said nozzle for said lower chamber, annular
15 passages in said nozzle between said discharge passages, one communicating with

the top of said lower chamber, and the other communicating with the top of said upper chamber, said annular passages communicating with each other at their tops, a vent for 20
25 said lower chamber, said lower chamber venting said upper chamber through said communicating passages, and a plurality of openings at different levels between said upper chamber discharge passage and one of said intermediate passages, whereby air will be admitted to said discharge passage as the upper chamber fuel level is lowered.

In testimony whereof I have hereunto subscribed my name.

CHARLES L. RAYFIELD.
